UNITED STATES PATENT OFFICE.

LEO L. PFEIFER, OF COLUMBUS, OHIO, ASSIGNOR TO THE JOHN W. BROWN MANUFACTURING COMPANY, OF COLUMBUS, OHIO, A CORPORATION OF OHIO.

LAMP.

1,186,605.

Specification of Letters Patent. Patented June 13, 1916.

Application filed December 20, 1915. Serial No. 67,772.

To all whom it may concern:

Be it known that I, LEO L. PFEIFER, a citizen of the United States, residing at Columbus, in the county of Franklin and State of Ohio, have invented certain new and useful Improvements in Lamps, of which the following is a specification.

This invention relates to lamps and aims particularly to provide a type of lamp which is serviceable or adaptable as automobile headlights. In automobile headlight construction, one of the essential features to guard against is the possibility of rattle and the admission of dust or moisture to the reflecting surface. The former is bothersome, in that the noise attending rattle is undesirable and further causes an unnatural wear of the parts; while the latter causes the deterioration of the reflecting properties of the reflector, thus decreasing the amount of light cast upon the roadway ahead.

It is, therefore, the main object of this invention to provide a peculiar construction of attachment between the lamp body and its reflector and the lens supporting structure, whereby these three component parts are securely held in position to preclude the possibility of rattle and vibration. Essentially, this results from the shelf structure surrounding the open end of the lamp body and the flange projecting outwardly from the large end of the reflector body.

The preferred embodiment of my invention is shown in the accompanying sheet of drawings, in which similar characters of reference designate corresponding parts, and in which:

Figure 1 is a cross section taken through one of my lamps, Fig. 2 is a section taken on line 2—2 of Fig. 1 and looking in the direction of the arrows. Fig. 3 is a section taken on line 3—3 of Fig. 1 and looking in the direction of the arrows, and, Fig. 4 is a section taken on line 4—4 of Fig. 1 and looking in the direction of the arrows.

In these several views, the lamp body is designated by the reference numeral 1 and its general outline is such as will conform gracefully with the shape of the parabolic reflector shown at 2. The outer end of the body 1 is open, as is shown, and is bounded by a cylindrical portion 3 which acts as a base for the support of an annular angle member designated 4. It will be noted that the two legs of this angle member are at

right angles to each other and that the leg 5 projects inwardly to form a shelf. The enlarged end of the reflector 2 is spun to present an outwardly extending flange 6, which flange is provided with a bead 7, 60 in which the dust cord 8 seats itself. The outer edge of the flange is also then turned down, as is shown at 9, this down-turned portion being preferably rounded as is shown, although this rounded structure is 65 not absolutely essential. From an inspection of Fig. 1, it will be noted that the diameter presented by the outermost edge of the flange 6 is larger than the diameter presented by the innermost edge of the shelf 70 5 and in fact, it is desired that the down turned portion 9 of the flange 6 shall have its bearing contact on the outer edge of the flange 5. The dust cord 8 is provided to serve as a compression member to coöperate 75 with the lens supporting structure now to be described, in order that this lens supporting structure may be held in firm engagement with the remaining structure and also prevent the ingress of dirt and moisture. 80

The lens supporting structure comprises an outer ring 10 of somewhat larger diameter than the diameter of the cylindrical portion 4 of the lamp body and is of any desired configuration. This ring is preferably lined with a strap 11, one leg of which is shaped to snugly fit the cylindrical portion 4, while the remaining portion is bent at right angles as is shown at 12 and then again bent at right angles as is shown at 13 to rest against the inner surface of the ring 10. The diameter presented by the bend 13 is greater than the diameter presented by the edge 14 of the ring 10 and it is in this space that the lens 15 is seated. 95 Portions of the leg 12 are stamped out to form tongues 16 and these tongues are then bent over the edge of the lens 15 to form the means of securely holding this lens in position. 100

It will be noted that the dust cord 8 is located in a bead which is of a considerably smaller diameter than the diameter of the turned down portion 9 and consequently by bringing the lens supporting structure into 105 tight engagement with this dust cord, so as to compress it slightly, the reflector will also be held in solid engagement with the lamp supporting structure. Because of the distance between the points of engagement 110

of the rim or turned down portion 9 of the body 1 and the lens supporting structure with the cord 8 any slight inequalities or imperfections of workmanship may be compensated for by the slight bending or distorting of the various metallic parts when the lens supporting structure is brought into firm engagement with the remaining structure. To effect this firm engagement and 10 to hold the lens supporting structure locked in its position, I have provided a plurality of hook members 17, which hook members are soldered or otherwise secured to the body 1, as may be desired. The flange portion 15 of the reflector itself is cut out as is shown at 18 to accommodate the free passage of the reflector over the hooked portions 19. After the reflector has been set in position by passage over these hooks, the 20 lens supporting structure itself may be locked into engagement with the hooked portions 19 by the proper placing of this lens supporting structure to the position shown in Fig. 1, wherein the hook portions 25 19 pass through the cut out portions 20 in the leg 12 of the lining member 11. A slight rotative movement then brings the hook portion 19 into the space between the member 11 and the outer ring 10, thus bringing 30 it into holding engagement with the portion 12 of the member 11. This hook may also be provided with a cam portion 21 if desired and the member 11 is provided with a slight depression such as is shown at 35 22 whereby the user is assured that the lens supporting structure may not accidentally become disengaged.

Because of the distance between the bearing points of the reflector on the body portion 40 and the lens supporting structure on the reflector, all of the component parts may be securely held in position if the hook members are properly located to wedge themselves into engagement with the lining member 11 located in the ring member 10. By 45 the proper degree of compression of the dust cord 8, all dust and moisture may be excluded and a lamp of comparative cheapness may be provided.

What I claim is:

1. In a lamp, a body member having an open end, a shelf around the open portion, a reflector located within said body and

provided with a flared outwardly extending flange, the outer edge of said flange being designed to lie on said shelf with its inner portion free of said shelf, a lens and lens support, and connecting means for holding said lens support against said reflector flange. 55 60

2. In a lamp, a body member having an open end, a shelf around the open portion, a reflector located within said body and provided with a flared outwardly extending flange, said flange being of a larger diameter than the inner diameter of said shelf, the edge of said flange being turned down to rest on said shelf, a lens and lens support, and connecting means for holding said lens support against the reflector flange, the bearing contact of said support on said flange being inward of the support of said flange on said shelf. 65 70

3. In a lamp, a body member having an open end, a shelf around the open portion, a reflector having suitable spaced cut-out portions located within said body and provided with a flared outwardly extending flange, said flange being of a larger diameter than the inner diameter of said shelf, the edge of said flange being turned down to rest on said shelf, hooks carried by said body and extending through the cut out portions of said reflector flange, the hook portions of said hooks projecting in a direction substantially parallel with said flange and shelf, and a lens and lens support, said lens support being constructed to coöperate with said hooks to securely hold it in position against said reflector flange. 75 80 85 90

4. In a lamp, a body member having an open end, a reflector located within said body, a lens support, means for detachably connecting said lens support in connection with said body, and means for holding the lens in position in said support comprising tongues stamped out of the metal lens support and turned over to grip the edge of the lens. 95

In testimony whereof I affix my signature in presence of two witnesses.

LEO L. PFEIFER.
